CONVERTIBLE HIGH CHAIR AND
BABY WALKER

Alfred Klazkin, Brooklyn, N. Y.

Application June 26, 1934, Serial No. 732,522

2 Claims. (Cl. 155—41)

This invention relates to convertible infants' high chairs and has for its principal object to provide a high chair which by a simple adjustment may be easily converted into a baby walker 5 which will afford to the infant adequate protection against injury during the period in which the infant is learning to walk.

A further object of my invention is to provide a high chair in combination with a baby walker, 10 both of which may be conveniently adjusted to any desired height, the chair being easily changeable to provide a toilet seat for the infant.

The invention will be fully and comprehensively understood from a consideration of the following 15 detailed description when read in connection with the accompanying drawings which form part of the application, with the understanding, however, that the improvement is capable of extended application and is not confined to the exact showing 20 of the drawings nor to the precise construction described and, therefore, such changes and modifications may be made therein as do not affect the spirit of the invention nor exceed the scope thereof as expressed in the appended claims.

In describing the invention in detail and the 25 particular physical embodiment illustrating the invention, reference is had to the accompanying drawings wherein like characters of reference designate corresponding parts thruout the several views.

In the drawings:

Fig. 1 is a perspective view of my device used 30 as a high chair.

Fig. 2 is a vertical transverse sectional view of 35 the device as shown in Fig. 1.

Fig. 3 is a horizontal sectional view illustrating 40 the adjustment mechanism.

Fig. 4 is a perspective view of the device used 45 as a baby walker.

Fig. 5 is a vertical transverse sectional view of 50 the baby walker as shown in Fig. 4; and

Fig. 6 is a horizontal sectional view taken on 55 line 6—6 of Fig. 5.

Referring to the drawings for a more detailed 45 description thereof, the convertible high chair of my invention comprises substantially two units, a lower section or base 7 and an upper section 8 adapted to be lowered and telescope into the lower section 7, the desired relative position of 50 the sections being secured by the adjustment mechanism 9 illustrated in detail in Fig. 3. The upper section is provided at its top with a frame or rim 10 to which is hingedly mounted at its rear interior edge a seat 11, the center of which 55 is provided with a removable oval cover 12. The

seat 11 has a spring latch 11a on its lower surface, adjacent its front edge, and is adapted to enter an opening 11b in the front member of the flange 10 for the purpose of holding the seat in horizontal position. A back rest 13 is rigidly 5 secured to the rear of frame 10 and provides partial support for a tray 14, which tray is pivotally mounted to the back rest 13, the front edge of the tray 14 being supported on the hinged strap 15, the same being removably secured to 10 tray 14 by the pin 16. A pair of flanged cleats 17 are fastened to the underside of the seat 11 to facilitate the placement of a chamber in place within the chair, a door 18 being provided in one side of upper section 8 for access to same. 15

In the physical embodiment of my invention the construction of the upper and lower sections comprises vertical corner members 20 and 21, respectively, the lower corner members being joined by side panels 22 and the upper corner 20 members being joined by panels 23. As shown clearly in Figs. 3 and 6, corner members 21 of the upper section 8 are slidably held by the interior surfaces of the corner members 20 of the lower section 7. 25

To facilitate the convenient setting of the chair to any desired height or the conversion of same to be used as a baby carrier, I have provided an adjustment mechanism 9, illustrated in Fig. 3. This mechanism comprises substantially two laterally disposed ratchet rods 24 in axial alignment, their adjacent ends being engaged by a compression spring 25 provided to push the rods outwardly. Rods 24 are provided with handles 26 extending thru a slot 28, the handles providing 30 means by which the rods may be readily moved toward each other against the pressure of spring 25. The free ends of the rods 24 pass thru corners 21 of the upper section 8 and engage in ratchets 27 formed in the interior surface of corner members 20 of the lower section 7. 35

A walker saddle 30, being resiliently suspended on the upper section 8 by straps 31 and springs 32, is of such shape that the child may sit astride of same, thus permitting its legs to touch the floor so that altho the major portion of the child's weight is supported on the saddle the child may attempt to walk without any danger of falling. 45

To convert my adjustable high chair to a baby walker it is necessary merely to swing back tray 50 14 to the position shown in Fig. 5, release seat 11 to its vertical position and then lower the entire upper section by releasing the adjustment mechanism 9. The setting of my device for this particular use is shown clearly in Figs. 4 and 5. 55

It is obvious from the drawings that the adjustment of the high chair to any desired elevation may be easily accomplished and further that the conversion of the high chair into a baby 5 walker can easily be done without the removal of any of the parts.

What is claimed as new and useful is:

1. An article of the character described as a combination high chair and walker, comprising a 10 first hollow structure open throughout from top to bottom, both inclusive, so that a child may be placed therein with its feet on the floor, said first structure being provided with wheels for contact with the floor, a second hollow structure open at 15 the top and bottom and telescoping with said first structure and adjustable vertically relative thereto, a seat closing the top of said second structure for use when the article is used as a high chair, said seat being movable from operative position 20 to open the top of said upper structure, and a second seat for use when the article is used as a walker and secured to one of said structures below the first mentioned seat, there being spaces for the legs of the child between said second seat and the walls of said second structure.

below the first mentioned seat, there being spaces for the legs of the child between said second seat and the walls of said second structure.

2. An article of the character described as a combination high chair and walker, comprising a 5 first hollow structure open thruout from top to bottom, both inclusive, so that a child may be placed therein with its feet on the floor, said structure being provided with wheels for contact with the floor, a second hollow structure open at 10 the top and bottom and supported by said first structure and adjustable vertically relative thereto, a seat closing the top of said second structure for use when the article is used as a high chair, said seat being movable from operative position 15 to open the top of said upper structure, and a second seat for use when the article is used as a walker and secured to one of said structures below the first mentioned seat, there being spaces for the legs of the child between said second seat and 20 the walls of said second structure.

ALFRED KLAZKIN.
